UNITED STATES PATENT OFFICE.

WILLIAM D. TABER, OF ROCKVILLE, RHODE ISLAND, ASSIGNOR TO HIMSELF, CLARK A. TABER, OF SAME PLACE, AND JOHN A. COREY, OF HOPE VALLEY, RHODE ISLAND.

CHECK-REIN HOLDER.

SPECIFICATION forming part of Letters Patent No. 333,031, dated December 22, 1885.

Application filed June 25, 1885. Serial No. 169,738. (No model.)

To all whom it may concern:

Be it known that I, WILLIAM D. TABER, of Rockville, in the county of Washington and State of Rhode Island, have invented a new and Improved Check-Rein Holder, of which the following is a full, clear, and exact description.

My invention relates to that class of devices that are attached to harness-saddles, and are employed to hold and retain the check-reins, by means of which horses' heads are held to a certain elevation; and the object of my invention is to provide a holder by which the check-rein can be quickly adjusted to a proper length.

Reference is to be had to the accompanying drawings, forming a part of this specification, in which similar letters of reference indicate corresponding parts in both the figures.

Figure 1 is a side view of my improved check-rein holder, being shown partly in section on line *x x* of Fig. 2; and Fig. 2 is a rear view of the holder.

Instead of the usual hook that is centrally secured to the saddle, I employ a rectangular metallic frame, as *A*, which is secured to the saddle in the ordinary manner by means of a bolt, as *a*, which is threaded to engage with a nut, as *b*. A cam-faced clamping-tongue, *B*, is loosely mounted on a bolt or rod, as *c*, that is passed transversely through the upper part of the frame *A*, said tongue being arranged to closely approach the lower interior surface, *d*, of the frame *A*. The surface *d* is slightly beveled, as clearly shown in Fig. 1, its higher side being toward the front of the holder. The cam-face *e* of the tongue *B* is corrugated and formed so that the rear edge of the cam-face is the point farthest removed from the center of motion of the tongue, and consequently the point nearest the beveled surface *d* of the frame *A*. One side of the upper portion of the tongue *B* is cut away, in order that a spiral spring, as *f*, may be coiled about

a sleeve, as *i*, that is carried by the bolt *c*, upon which, as before stated, the tongue *B* is loosely mounted. One end of the spring *f* bears against the upper face of the opening formed in the frame *A*, while the other end

is bent out at right angles, so as to be about 50 parallel with the bolt *c*, and bears against the rear of the tongue *B*, the tendency of the spring being to throw the tongue over in the direction of the arrow shown in Fig. 1 until the tongue abuts against the stop or limit 55 pin *o*.

In connection with the apparatus first described I employ a strap to which a snap-hook, as *D*, is attached by means of a strip, *g*, made of rawhide or other suitable strong 60 but thin material. The main body of the strap *C* is much thicker than the rawhide *g*, and is also thicker than the free end of the strap shown at *h*.

The operation of the holder is as follows: 65 The hook *D* having been secured to the check-rein and the end *h* of the strap *C* having been passed through the space intervening between the cam-face *e* of tongue *B* and the beveled surface *d* of the frame *A* is pulled to the 70 rear until the thick portion *k* of the strap *C* is brought above the surface *d*. As soon as the thick portion *k* comes over the surface *d*, the upper side of the strap will strike against the corrugated cam-face *e*, and the tongue *B* 75 will be carried to the rear, when, if the pressure used in pulling the strap *C* is relaxed, the spring *f* will act to slightly force the cam-face *e* up on the upper side of the strap, and any pull upon the hook *D* will only tend to 80 tighten the grip of the tongue upon the strap. If it is desired to relax the strap, it is first pulled through until the rawhide *g* is beneath the tongue *B*, when the spring *f* will immediately carry the tongue forward until it 85 abuts against the pin *o*, and when the tongue is in this position the strap *C* can easily be pulled forward until the thin portion *h* is beneath the tongue.

Such a holder as I have described is simple 90 in construction, durable, and can be quickly adjusted so as to hold the horse's head to the desired elevation.

Having thus fully described my invention, I claim as new and desire to secure by Letters 95 Patent—

1. The combination, with a strap, as *C*, of a frame, as *A*, carrying a tongue, as *B*, formed

with a cam-face, *e*, a spring, as *f*, and a pin, as *o*, substantially as described.

2. The combination, with a frame, as *A*, formed with a beveled surface, as *d*, of a cam-faced tongue, *B*, that is borne upon by a spring, *f*, substantially as described.

3. The combination, with a holder, substantially as described, of a strap carrying a hook, as *D*, connected to the main body *k* by a strip, *g*, substantially as described.

4. The combination, with a holder, substantially as described, of a strap consisting of the

portions *g*, *k*, and *h*, and carrying a hook, as *D*, substantially as described.

5. As a new article of manufacture, a check-rein holder consisting of a frame, as *A*, in which there is loosely pivoted a cam-faced tongue, as *B*, that is controlled by a spring, as *f*, substantially as described, and for the purpose specified. 15

WILLIAM D. TABER.
